UNITED STATES PATENT OFFICE

157,118

PNEUMATIC TIRE CASING

George W. Anderson, Akron, Ohio, assignor to
The General Tire & Rubber Company, Akron,
Ohio, a corporation of Ohio

Application October 29, 1947, Serial No. 142,184

Term of patent 14 years

(Cl. D90—20)

To all whom it may concern:

Be it known that I, George W. Anderson, a citizen of the United States of America, residing at Akron, in the county of Summit and State of Ohio, have invented a new, original, and ornamental Design for a Pneumatic Tire Casing, of which the following is a specification, reference being had to the accompanying drawing, forming a part thereof, in which the figure is a perspective view of a pneumatic tire casing, showing my new design.

I claim:

The ornamental design for a pneumatic tire casing, as shown.

GEORGE W. ANDERSON.
